UNITED STATES PATENT OFFICE.

WILLIAM H. JAY, OF PROVIDENCE, RHODE ISLAND.

SCREW-PROPELLER.

SPECIFICATION forming part of Letters Patent No. 528,253, dated October 30, 1894.

Application filed December 13, 1892. Serial No. 455,032. (No model.)

To all whom it may concern:

Be it known that I, WILLIAM H. JAY, a citizen of the United States, residing at Providence, in the county of Providence and State 5 of Rhode Island, have invented certain new and useful Improvements in Screw-Propellers; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 My invention has relation to screw-propellers, but more particularly to a novel construction of the blades or wings. Usually heretofore, so far as I am aware, screws of this character have been provided with blades 20 having the length of the forward or entering side or edge substantially the same as the rear or discharging side. Moreover, such former screws have been practically alike as regards the form of the two radial edges of 25 the blades. By reason of such construction the blade in working enters the water at its full leverage and pressure, thereby subjecting the shaft and motive power to a continuous series of shocks or jars which act not only 30 to shorten the life of the machinery but at the same time produce a disagreeable sensation and noise.

The object I have in view is to overcome the defects or disadvantages just referred to. 35 To that end my invention consists, essentially, of a screw-propeller having the entering edge and a small area of each blade formed with a slightly greater inclination or pitch than the major portion of the blade while the rear or 40 discharging edge is reversely bent or curved. The outer peripheral edge of the blade is non-concentric with the shaft, its greatest radius being at the rear edge, and its greatest width near the hub of the screw. By means of this 45 construction and arrangement the blades are adapted to enter the water easier; the gradually increasing area of the blade causing it to cut through the water with less slip, and consequently greater efficiency; the curved 50 portion of the rear edge of the blade at the same time operating to prevent a too free release of the impinging water from the work-

ing face of the blade, all as will be more fully hereinafter set forth and claimed.

In the accompanying sheet of drawings, 55 Figure 1 is a side elevation of a screw-propeller embodying my improvement. Fig. 2 is an end view. Fig. 3 is a perspective view, viewed at right angles with the plane of the blade, and Fig. 4 is a transverse sectional view, taken on line $\alpha\alpha$ of Fig. 1.

In carrying out my improvement I would state that neither the hub of the wheel nor the manner of securing the blades thereto form any part of my present invention, as the 65 latter resides solely in the novel construction of the blade itself.

In the drawings A indicates a two-bladed screw-propeller provided with my improvement. The hub portion is designated by h , 70 and a indicates the blades. The blades as drawn are formed integral with the hub, but they may be made independently of it and secured thereto in any well known manner. The position or location of the blades with 75 reference to the hub is such that they stand at an oblique angle of about forty-five degrees (see Fig. 4), although the angle may be changed to suit varying conditions. The forward or entering portion b of the blade a is 80 bent inboard, or toward the vessel, as clearly shown in Fig. 4, thereby forming with the major portion of the working area a' , if continued, an acute angle m , as indicated by the broken line in said figure. When thus bent 85 or formed it will be seen that the blade will present a working surface having an included angle exceeding one hundred and eighty degrees, as indicated by the dotted curved line e , in the horizontal sectional view, Fig. 4. 90 The part a' of the working area forms a substantially plane or flat surface arranged obliquely with the hub. The rear or discharge edge c of the blade is bent in a reverse direction or toward the shaft, as shown and as 95 clearly represented in Fig. 4. The path described by the outer peripheral edge p is not a true circle n (see dotted lines Fig. 2) because I prefer to so make said edge that it is bounded or limited by radii having varying lengths. 100 By this arrangement the power exerted in propelling the vessel against the resistance or pressure of the water is more gradually utilized. At the same time the bent portion

of the rear edge c operates to prevent the water, impinging against the working surface a' of the blade, from escaping too readily, thereby decreasing the percentage of slip. I also prefer to make the widest portion of the blade at or near the hub, as indicated at $o o$, Fig. 3, thus greatly strengthening the blade as well as increasing the leverage at that point.

In screw-propellers of comparatively small diameter I prefer to employ two blades, but larger screws may have three or more.

I claim as new and desire to secure by United States Letters Patent—

1. A screw-propeller blade consisting essentially of a forward or leading portion b bent inboard and a main portion a' arranged at an angle therewith exceeding one hundred and eighty degrees, whereby the said leading portion of the blade has a coarser pitch than the main portion, substantially as described.

2. A screw-propeller blade having its forward portion bent inboard to form an obtuse angle with the plane of the major portion of the blade, and having its rear or releasing portion reversely bent toward the shaft, substantially as hereinbefore described and for the purpose set forth.

3. A screw-propeller blade having its outer

peripheral edge bounded by radial lines gradually increasing in length from the front to the rear, the front portion being bent inboard to form an obtuse angle with the plane of the major portion of the blade, its rear or releasing portion being reversely bent toward the shaft, and having the greatest width of the blade at or near the hub, substantially as hereinbefore described.

4. The screw-propeller, substantially as hereinbefore described, consisting of a hub portion adapted to be fixed to a driving-shaft, and having a plurality of bent blades a secured to or integral with said hub; each of said blades having a forward or leading portion b bent inboard and a main portion a' arranged at an angle therewith exceeding one hundred and eighty degrees, and having the rear or releasing portion c of said main part bent reversely toward the shaft, whereby the said leading portion of the blade has a coarser pitch than the main portion.

In testimony whereof I have affixed my signature in presence of two witnesses.

WILLIAM H. JAY.
